UNITED STATES PATENT OFFICE.

HENRY T. OFFTERDINGER, OF WASHINGTON, DISTRICT OF COLUMBIA,
ASSIGNOR TO THE PATENT FIN HOT WATER HEATING COMPANY,
OF WASHINGTON, DISTRICT OF COLUMBIA, A CORPORATION OF
VIRGINIA.

PORTABLE HOT-WATER RADIATOR.

No. 830,359.

Specification of Letters Patent.

Patented Sept. 4, 1906.

Application filed February 26, 1906. Serial No. 303,047.

To all whom it may concern:

Be it known that I, HENRY T. OFFTERDINGER, a citizen of the United States, residing at Washington, in the District of Columbia, have invented new and useful Improvements in Portable Hot-Water Radiators, of which the following is a specification.

My invention relates to improvements in portable hot-water heating apparatus of the radiator type—that is to say, apparatus in which water is caused to circulate through a series of radiator-sections, the combined sections making up the radiator being portable.

The object of the invention is to facilitate heating the circulating body of fluid to the end that a radiator supplied with my invention may have its body of circulating fluid quickly and intensely heated.

Radiators of the type to which this invention is directed are chiefly, although not exclusively, useful to heat rooms or apartments separate and apart from a permanent system designed to heat various rooms or apartments of a building. Such portable apparatus may be moved from place to place in a building and used wherever there be a connection for fuel, such as gas from an ordinary gas-fixture or the like. In the uses for which such apparatus is ordinarily designed it is a material consideration that the circulating body of fluid may be quickly and intensely heated, and this consideration is fully met in an apparatus embodying my invention.

With the foregoing object in view the invention consists in a portable hot-water heating apparatus or radiator possessing the features hereinafter described, and illustrated in the accompanying drawings.

That which is regarded as new will be set forth in the clauses of claim appended to the description.

In the accompanying drawings, illustrating that which I regard as the best known embodiment of my invention, Figure 1 is a part elevation and part sectional view of a radiator provided with my invention; Fig. 2, an end view; Fig. 3, a perspective of the members of the burner. Fig. 4 is a transverse section on line 4-4 of Fig. 1.

In the said drawings the reference-number 1 designates a hot-water radiator, which may be of any of the usual known types, and being unconnected with a perma-

nent or stationary heating system may be, if desired, provided with an expansion box or tank 2. Through this radiator the water is caused to circulate, and the same constitutes the effective heat-radiating medium for warming the room or other space in which the same is located. In order to quickly and intensely heat the water which circulates through the radiator, an additional device especially designed and calculated to accomplish this object is provided and combined with the radiator proper. Said device consists of a supplementary or auxiliary circulating-tube 3, which hereinafter or brevity will be referred to as a "heating-tube." The heating-tube 3 is vertically or substantially vertically disposed, so that there is an upward flow of the hereinafter-referred-to fluid column therethrough. The term "vertical" or "substantially vertical" is employed to convey the idea of this upward flow of the fluid column and is intended to include the substantial functional equivalent of the arrangement shown. The said tube is in communication at its opposite ends with the fluid-circulating system of the radiator by means of suitable couplings or connections 4 and is essentially of such construction or conformation as will compel the fluid passing therethrough to assume a film form, in which form the fluid body may be most quickly or readily and intensely heated. To the accomplishment of this end, the said auxiliary or supplementary tube comprises opposite parallel walls 5, closely associated and presenting relatively broad or extended surface areas capable of being subjected to the influence of a heating medium and compelling the water which passes therethrough to conform to the characteristic contour of the said supplementary or auxiliary heating-tube and assume the form of a fluid film, the attenuated character of which is most susceptible of responding to the influence of heat applied to the tube through which it passes.

The broad flat parallel walls of the heating-tube sustain a relation more intimate in respect to closeness to each other than do the walls of the columns of the radiator 1, and the circulation capacity of said heating-tube is sufficient to take care of the circulating capacity of the several columns of said radiator, so that the column of water passing

from the outlet end of the radiator is changed as to its form and made to come to a thin or film-like column by reason of the characteristic construction of the heating-tube. In 5 this form the thin film-like column of water passing through the heating-tube presents a great surface area as compared with the mass of the column to the influence of the burner next to be described. The fluid column 10 maintains the film-like form referred to throughout the heating-tube and in such form is subjected to the direct influence of the burner. Preferably and as shown the heating-tube is a vertical one, in which form 15 it is considered that the greatest efficiency is secured. This may be attributed to the probable formation of a thin stratum of vapor along the interior wall of the heating-tube, tending to travel rapidly through the 20 tube and exerting an accelerating influence on the fluid column within the tube.

Associated or combined with the auxiliary or supplementary heating-tube is a burner 6, the jet-orifices 7 of which extend across and 25 in nearness to the parallel walls of the tube. This burner entirely surrounds the tube and is preferably and as shown of the Bunsen type, having a conduit 8 for the supply of fuel, such as gas, and a regulable means 9 for 30 the supply of atmospheric air. The fuel may be oil or gas, as may be desired. For the purpose of confining the flame of the burner to exert its greatest efficiency upon the tube and its contents a jacket 10, conforming to 35 the external configuration of the tube, is provided surrounding the said tube and supported in suitable manner from the burner, as shown, having a slip fit about a preferably continuous flange 11, with which the burner 40 is provided. The jacket at its lower end adjacent the jet-orifices of the burner is provided with openings 12 for the ample supply of oxygen to support combustion, and at its upper end is provided with a slip-cap 13, 45 having openings 14, adapted to more or less register with, and therefore more or less open or entirely close, similar openings 15 in the jacket for the purpose of regulating the draft. By making the jacket conform to 50 the shape of the heating-tube the products of combustion are caused to impinge directly and equally against the walls of the heating-tube, and said jacket is closely associated with the heating-tube, a comparatively narrow space intervening between the same, so 55 that the maximum heating effect is secured.

In the practical use of portable hot-water radiators according to my invention means are provided whereby connection may be 60 made from either end of the burner. Frequently by reason of local surroundings radiators cannot with facility be used, because of the difficulty of connecting the same with the fuel-supply. According to my invention 65 the burner is provided with a duplex or plu-

ral means 16 of connection with the fuel-supply, either of which means may be closed by a cap 17, and the other or either of which may be connected with the fuel-supply. By the plural fuel-supply radiators embodying 70 my invention present great facility of conformance with local conditions.

The desirability of a portable hot-water heating apparatus, such as may be shifted from place to place or installed in various 75 situations and the circulating body of fluid of which may be quickly heated to accommodate exigencies where either stable or temporary but efficient and quickly responsive action is desired, has been felt and 80 the want is fully supplied by my invention.

Having thus described my invention, what I claim is—

1. In combination with a portable hot-water radiator, a vertically-disposed supplemental or auxiliary heating-tube having communication with the fluid-passages of the radiator and comprising walls which, as compared with the walls of the columns of the radiator proper, are closely associated to compel the fluid to pass therethrough in a thin film, a burner combined with and surrounding said heating-tube at the lower portion thereof, and a heat-confining jacket associated with the burner and surrounding the 95 heating-tube.

2. In combination with a portable hot-water radiator, a vertically-disposed supplemental or auxiliary heating-tube having communication with the fluid-passages of the radiator and comprising walls, which, as compared with the walls of the radiator proper, are relatively closely associated to compel the fluid to pass therethrough in a thin film, a burner combined with and surrounding 100 said heating-tube at the lower end thereof, and a heat-confining jacket surrounding and conforming to the shape of said heating-tube.

3. In combination with a portable hot-water radiator, a vertically-disposed supplemental or auxiliary heating-tube having communication with the fluid-passages of the radiator and comprising walls which, as compared with the walls of the columns of the radiator proper, are relatively closely associated to compel the fluid to pass therethrough in a thin film, a burner combined with and surrounding said heating-tube at the lower end thereof, a heat-confining jacket associated with the burner and surrounding 115 the heating-tube, and a draft-regulator connected with the said heat-confining jacket.

4. In combination with a portable hot-water radiator, a supplemental or auxiliary fluid-passage having communication at its 125 opposite ends with the radiator, said fluid-passage comprising closely-associated relatively broad walls to compel the fluid to pass therethrough in a thin film, a burner combined with and disposed at the lower end of 130

said fluid-passage, said burner having jet-openings arranged to direct jets of flame upward and in close contact with the opposite broad walls of the passage, and a heat-confining jacket surrounding and conforming substantially to the shape of the fluid-passage, the walls of the jacket being arranged in close proximity to the walls of the said passage whereby to provide a relatively narrow 5 to annular chamber thereabout to closely con-

fine the products of combustion issuing from the burner.

In testimony whereof I have hereunto set my hand in presence of two subscribing witnesses.

HENRY T. OFFTERDINGER.
